CONTROL SYSTEM

Willard G. Cook, Wilkinsburg, Pa., assignor to
 Westinghouse Electric & Manufacturing Company, East Pittsburgh, Pa., a corporation of Pennsylvania

Application April 25, 1939, Serial No. 269,906

15 Claims.

(Cl. 80—35)

My invention relates, generally, to control systems, and, more specifically, to systems for controlling the acceleration and deceleration of the roll and reel motors of a strip rolling mill.

In the operation of strip rolling mills employed in the manufacture of steel strip, it is desirable that a controlled tension be applied to the strip as it passes through the reducing rolls. The application of tension to the strip produces a greater degree of reduction of the strip thickness for a given reducing roll pressure at each roll stand, and thus reduces the number of roll stands necessary to produce a given total strip reduction at a given roll pressure, or reduces the roll pressure necessary to produce a given strip reduction in a given number of roll stands. The application of tension to the strip while rolling also produces certain desirable characteristics in the strip material, such as uniformity of the structure of the strip and uniformity of gauge throughout the width of the strip.

The amount of strip reduction for a given roll pressure is a function of the front and back tensions applied to the strip at the reducing rolls and for this reason, it is desirable that a substantially constant tension be applied to the strip to thereby secure uniform draft and produce a strip of uniform thickness.

As a pair of reducing rolls subjects a strip to reducing pressure and also subjects the strip to tension as it is delivered from the preceding roll stand, the total load on the motor driving the reducing rolls is comprised of components of friction load, tension load and rolling load while the speed of the rolls is constant. Since the friction and rolling loads are substantially constant for a given mill speed, it is only necessary to regulate the torque applied to the strip to produce uniform strip tension. This regulation of the strip tension has been accomplished in certain known strip rolling systems by a constant current regulator acting in response to the roll and reel motor armature current to control the motor field excitation.

While the mill is being brought up to speed, the total roll motor load is comprised of friction load, tension load, rolling load and acceleration load. If, then, the tension load is to remain constant during all conditions of acceleration and running, it will be necessary to provide additional current loading of the motor during the acceleration. In a like manner, during deceleration, the motor load must be decreased to compensate for the power supplied by the inertia of the rolls and the motor. However, the accelera-

tion and deceleration loads do not have a constant value throughout the acceleration and deceleration periods and it is necessary that the compensation be proportional to the rate of acceleration and deceleration in order to provide a substantially uniform tensioning load at all times.

In addition to the variation in the acceleration and deceleration loads, the friction load varies as a function of the speed of the mill, and it is also necessary to compensate for this motor load variation in order to provide a substantially uniform tensioning load at all times.

An object of my invention, therefore, is to provide a control system which shall function to control the torque delivered by a motor.

Another object of the invention is to provide a control system which shall function to control the power delivered by a motor.

20 A further object of the invention is to provide a motor control system which shall function to so control the load output of a motor which drives a work device as to cause a length of material which is being fed to and acted upon by

25 the work device to be subjected to a substantially constant tension regardless of the speed and acceleration or deceleration of the work device.

Another object of the invention is to provide a control system for a strip rolling mill which shall function to so control the roll motor for a roll stand of the mill as to maintain a substantially constant tension on the strip as it is fed to the roll stand from the preceding roll stand regardless of the speed and changes of speed of the mill.

30 Still another object of the invention is to provide a control system for a strip rolling mill which shall function to so control a reel motor of the mill as to maintain a substantially constant tension on the strip as it is wound upon or unwound from the reel regardless of the speed and changes of speed of the mill.

These and other objects and advantages of the invention will be apparent from the following detailed description taken in connection with the accompanying drawings in which:

Figure 1 is a diagrammatic view of an acceleration control system for a roll motor of a strip rolling mill embodying the principal features of my invention; and

Fig. 2 is a diagrammatic view of an acceleration control system for a reel motor of a strip rolling mill embodying the principal features of my invention.

55 Identical and similar reference characters des-

gnate identical and corresponding elements in the two figures of the drawings.

In carrying out the invention, I provide, in the embodiment of Fig. 1, a continuously-driven main generator 2 whose output potential may be varied to control the energization and, therefore, the speed of the armatures of the drive motors 4 and 6 for the roll stands 8 and 10. As the strip 12 passes between the roll stands in the direction indicated by the arrow, it is subjected to tension by the pulling action of the rolls of the roll stand 10.

The tension on the strip 12 is maintained substantially constant by a regulator 14 which functions to vary the excitation of the motor 6 in response to variations of the load on the motor as measured by its armature current.

A pilot generator 16 driven by the motor 6 or by any suitable means at a speed proportional to that of the motor 6, is connected to vary the energization of a solenoid-operated rheostat 18 through a transformer 20 in accordance with the acceleration and deceleration of the motor 6. The rheostat 18 is connected to an operating circuit of the regulator 14 to vary the calibration of the regulator 14 in accordance with changes of the speed of the motor 6 to thus permit the necessary variations of motor current during acceleration and deceleration to maintain substantially constant strip tension. The energization of the regulator is also varied in accordance with the speed of the mill motor 8 to compensate for variations of the friction load of the mill and its driving motor due to speed variations of the mill.

In the embodiment of the invention shown in Fig. 2, the regulator 14 is automatically adjusted by the rheostat 18, which is actuated by the pilot generator 16 through the transformer 20, and operates to control reel motor 8' to maintain the desired tension on the strip 12 as it is received from the roll stand 8 and wound upon the reel 11. In this embodiment of the invention, the pilot generator 16 is driven by the drive motor 4 of the preceding roll stand 8.

Referring again to Fig. 1, the main generator 2 may be continuously driven at a substantially constant speed by any suitable motor or driving unit 22. The field winding 24 of the generator 2 is energized from any suitable source of direct-current power indicated by the bus A-B through a rheostat 26 which may be actuated to vary the energization of the field winding 24 and thus vary the output potential of the generator 2. The main generator 2 is connected to energize a main bus indicated by the conductors X-Y and the motors 4 and 6 are connected through suitable controllers as indicated to the bus X-Y.

The field windings 28 and 30 of the motors 4 and 6 are connected to be energized from the bus A-B through rheostats 32 and 34, which may be adjusted to provide the base speeds for the motors 4 and 6. A resistance element 38 is also connected in circuit with the field winding 30 of the motor 6 and contact elements 38 and 40 of the regulator 14 are connected to the respective ends of the resistance element 38 by means of conductors 42 and 44, to provide a shunting circuit for the resistance element 38 when the contact elements 38 and 40 are engaged.

The contact element 40 is fixed and the contact element 38 is mounted upon a pivoted arm 46 for movement therewith. The pivoted arm 46 is biased by the spring 48 to move the contact element 38 away from the contact element 40, and an armature 50 is secured to the pivoted arm 46

to actuate the arm to move the contact element 38 into engagement with the contact element 40. A winding 52 is associated with the armature 50 and is connected to be energized in accordance with the armature current of the motor 6, in a circuit which extends from one side of the series field winding 54 of the motor 6 through the conductor 56, a rheostat 58, a conductor 60, the winding 52, a conductor 62, the resistance 64 of the rheostat 18, and a conductor 65 to the other side of the series field winding 54.

The resistance element 64 of the rheostat 18 has a series of taps as indicated, each connected to a different one of a series of spaced conducting leaf spring elements 66 which are suitably insulated from each other and have one end mounted in a fixed position. Each of the spring elements 66 has a contact element 68 mounted thereon, the contact elements 68 being so disposed as to provide a connection between each successive spring element and the adjacent spring element as a force is applied to the top spring element to deflect the spring elements downwardly. In their normal undeflected positions, the spring elements 66 are disposed with their ends engaging the member 70 of insulating material to hold them in a position with all of the contact elements 68 disengaged.

The stack of spring elements 66 may be actuated to successively shunt out the desired number of sections of the resistance element 64 by the energization of a solenoid 72 having windings 74 and 76 actuating the armature 78 thereof, which in turn, actuates a pin 79 engaging the topmost of the spring elements 66. The armature 78 of the solenoid 72 is normally biased by means of a spring 80 to permit all of the contact elements 68 to rest in the open circuit position. The winding 76 is connected to be continuously energized from the bus A-B through a rheostat 82, by which the amount of energization of the winding 76 may be adjusted. The energization of the winding 76 is such as to normally bias the armature 78 of the solenoid 72 to actuate a portion of the spring elements 66 to shunt out a portion of the sections of the resistance element 64, to thereby provide an increased or decreased effective resistance of the rheostat 18 by decreased or increased deflection of the spring elements 66. As indicated in the drawings, the three uppermost spring elements 66 have been actuated out of engagement with the element 70 to provide engagement of the contact elements 68 associated therewith, and thus shunting out the three uppermost sections of the resistance element 64.

It will be understood that increased downward deflection of the spring elements 66 by increased actuation of the armature 78 will cause a shunting out of an increased number of sections of the resistance element 64 and that a decreased downward deflection will relieve the shunting circuit from successive sections of the resistance element 64. The winding 74 of the solenoid 72 is connected to be energized by the secondary winding 84 of the transformer 20 whose primary winding 86 is connected by means of conductors 88 and 90 to the armature of the pilot generator 16.

The field winding 92 of the pilot generator 16 is connected to be continuously energized from the bus A-B through a rheostat 94 by which the excitation of the pilot generator 16 may be adjusted.

It will be understood from this circuit arrangement that the winding 74 of the solenoid 72 will be energized in accordance with the rate of

change of the speed of the motor 6, since the secondary winding 84 of the transformer 20 will have potential induced in it only when the output potential of the pilot generator 16 is changing, due to acceleration or deceleration of the motor 6, and that the potential induced in the secondary winding 84 will be proportional to the rate of change of the speed of the motor 6. The polarity of the potential induced in the secondary winding 84 will also depend upon the direction of the change in the speed of the motor 6, that is, it will depend upon whether the motor 6 is accelerating or decelerating, and the relation of the windings 74 and 76 is such as to cause the coil 74 to buck the actuation of the armature 18 provided by the winding 76 when the motor 6 is accelerating to thus provide an increase in the effective resistance of the resistance element 64, and to add to the actuation of the armature 18 when the motor 6 is decelerating to thus decrease the effective resistance of the resistance element 64.

Thus, it will be apparent in the operation of the system to energize the winding 52 of the regulator 14, that the winding 52 thereof will be energized proportionately with the armature current of the motor 6, but that the energizing effect upon the winding 52 will be varied by the rheostat 18 in accordance with the change of speed of the motor 6 and in proportion to its rate of change of speed.

The regulator 14 further comprises a fixed armature member 96 upon which are disposed windings 98 and 100. The winding 100 is continuously energized from the bus A-B through a rheostat 102, by which the degree of energization of the winding 100 may be selectively adjusted. The winding 98 is connected to be energized in accordance with the generated potential of the pilot generator 16 through a suitable rheostat 104 in a circuit which extends from one side of the generator 16 through the conductor 90, a conductor 106, the winding 98, a conductor 108, the rheostat 104, a conductor 110 and the conductor 88 to the other side of the generator 16. Thus, it will be apparent that the regulator 14 is further adjusted in its operation in accordance with the speed of the motor 6, since the output potential of the pilot generator 16 is proportional to the speed of the motor 6.

In the operation of the system, it will be understood that, with the motors 4 and 6 running at a constant speed, the torque developed by the motor 6 will be made up of components of the torque required to overcome the friction of the motor 6, the rolling load on the roll 10 and the tension load due to the tension applied to the strip 12 as it is delivered from the roll stand 8 to the roll stand 10. Since for a given speed the rolling load and the friction load remain substantially constant, the tension load will remain constant if the total load of the motor is maintained constant. The regulator 14 operates to maintain the load on the motor constant by moving contact element 38 into engagement with contact 40 to thus increase the excitation of the motor 6 and tend to decrease its speed when the armature current of the motor 6 increases beyond a predetermined amount. This tendency to decrease the speed of the motor 6 will tend to decrease the output of the motor 6 and thus decrease the tension on the strip 12. This operation of the regulator 14 is intermittent and the excitation of the motor 6 is continuously being increased and decreased to provide the proper ad-

justment of the excitation, the relative amounts of the increases and decreases of excitation of the motor 6 being controlled by the armature current of the motor 6 through the regulator 14.

If now it is desired to increase the speed of the motors 4 and 6, the output potential of the main generator 2 may be increased by decreasing the effective resistance of the rheostat 26 to increase the armature potential of the motors 4 and 6. While the motors 4 and 6 are accelerating, the developed load of the motors will have to be increased an amount equal to the required accelerating torque if the torque applied to the strip 12 by the motor 6 in the form of strip tension is to be maintained constant, since the developed load of the motor 6 while it is accelerating, is equal to the tensioning load, the friction load of the motor and the mill 10, the rolling load, and the accelerating load. While this acceleration is taking place, the regulator 14 is readjusted or recalibrated to maintain a higher developed load on the motor 6, as hereinbefore described, through the actuation of the solenoid 72 by the change in speed of the motor 6 and, therefore, the output potential of the pilot generator 16 to increase the effective resistance of the resistance element 64 of the rheostat 18 to thus permit a larger armature current to flow to produce a given adjusting effect of the regulator 14 on the excitation of the motor 6. Since the acceleration component of the motor armature current is not directly proportional to the rate of acceleration of the motor, the different sections of the tapped resistance element 64 have different resistance values so as to provide current adjustments of the regulator 14 corresponding to the rate of motor acceleration. It is to be understood that any number of sections of the resistance element 64 with their corresponding control contact elements 68 may be provided.

Since the friction load on the motor also increased with increase of the speed of the motor in the mill, it is necessary to readjust the regulator 14 to provide for this extra developed load of the motor 6, and this is provided as hereinbefore described, by the increased energization of the winding 98 of the regulator 14 by the increased output potential of the pilot generator 16.

In a similar manner, when the mill is decelerated, the regulator 14 will be readjusted through the rheostat 18 by the decrease in output potential of the pilot generator 16 to compensate for the torque provided by the inertia of the moving parts of the motor 6 and the mill stand 10 to increase the effectiveness of the armature current of the motor 6 upon the regulator 14, and thus permit the regulator 14 to maintain a lower output load on the motor 6, and at the same time provide the same amount of tensioning load upon the motor 6.

The system of load regulation for the motor 6 may be applied to any number of the drive motors for the separately driven roll stands of a tandem strip rolling mill, and each such system will provide a substantially constant back tension on the strip as it enters the rolls of the roll stand whose drive motor is so regulated. It is to be understood that the rheostats 58 and 104 are provided for securing the proper adjustment of the energization of the coils of the windings in whose circuit they are connected, and that any equivalent of the rheostat 18 and the regulator 14 may be substituted for those illustrated and described in detail herein. It is to be further understood that any equivalent element may be substituted

for the pilot generator 16 so long as such equivalent element provides a potential which is proportional to the speed of the motor 6.

In the embodiment of the invention shown in Fig. 2, the system is substantially the same as that of Fig. 1, except that the winding tension on the strip 12 is regulated by the control of the motor 6' which drives the reel 11. The energization of the field winding 30' of the motor 6' is controlled by the regulator 14 in the manner explained hereinbefore in connection with the operation of the regulator 14 to control the roll motor 6 of the embodiment of Fig. 1. Likewise, the coil 52 of the regulator 14 is connected to be energized by the potential drop across the series field winding 54.

The pilot generator 16 is driven by the roll motor 4 instead of the motor 6' whose output it controls in this embodiment of the invention, since the speed of the roll stand 8 is a measure of the strip speed as it is wound on the reel 11. The speed of the motor 6' is not a measure of the strip speed since the speed of the reel 11 is continuously varying because of the "build-up" of strip on the reel.

The embodiment of the invention of Fig. 2 is also applicable to the control of the tension on the strip at the unwinding reel. In applying the system to the unwinding reel, the reel motor acts as a drag generator, or regenerative brake, and the pilot generator 16 is connected to be driven by the roll motor of the first roll stand.

While the system herein shown has been described as operating in connection with a strip rolling mill, it is to be understood that it is equally applicable to any system in which work devices operate upon a strip or web as it passes therethrough and apply tensions to the strip or web such as printing machines, paper manufacturing apparatus or cloth manufacturing or working machines.

It will be seen that I have provided a motor control system which shall function to so control the load output of a motor which drives a work device as to cause a length of material which is fed to and acted upon by the work device, to be subjected to a substantially constant tension regardless of the speed and acceleration or deceleration of the work device, which is simple and efficient in operation and inexpensive to manufacture, install and maintain.

In compliance with the requirements of the patent statutes, I have shown and described herein a preferred embodiment of my invention. It is to be understood, however, that the invention is not limited to the precise constructions shown herein, but is capable of modification by one skilled in the art, the embodiment herein shown and described being merely illustrative of the principles of my invention.

I claim as my invention:

1. In a system of control for a motor connected to a source of energy and driving a load, control means responsive to the load, the speed, and acceleration and deceleration of the motor for so controlling the excitation thereof as to maintain the torque delivered by the motor to the load at substantially constant value regardless of changes in motor speed.

2. In a system of control for a motor connected to a source of energy and driving a load, regulator means responsive to the armature current of the motor for controlling the excitation of the motor, motor speed controlled acceleration and deceleration responsive means for varying the

energizing effect per unit of the motor armature current upon said regulator means in accordance with the motor acceleration and deceleration, and means responsive to the speed of the motor for varying the energization of said regulator means in accordance with the motor speed, whereby the torque delivered by the motor to the load is maintained substantially constant throughout a desired range of motor speed.

3. In a control system for maintaining the torque delivered by a motor to a load to which it is connected substantially constant throughout a desired range of speed of the motor, means responsive to the motor speed for varying the friction component of the developed motor torque in accordance with the rate of speed of the motor, and motor speed controlled means responsive to the motor acceleration and deceleration for varying the acceleration and deceleration component of the developed motor torque in accordance with the rate of acceleration and deceleration of the motor whereby the delivered motor torque will remain substantially constant throughout the desired range of motor speed.

4. In a motor control system, regulator means responsive to the armature current of the motor for maintaining the developed torque of the motor substantially constant for a given motor speed, a transformer, means responsive to the motor speed for continuously energizing the primary winding of said transformer with a direct current potential proportional to the speed of the motor, and means responsive to the potential induced in the secondary winding of said transformer for causing said regulator means to vary the developed motor torque in accordance with the acceleration and deceleration of the motor.

5. In a control system for maintaining the torque delivered by a motor to a load to which it is connected substantially constant throughout a desired range of speed of the motor, means responsive to the motor speed for varying the friction component of the developed motor torque in accordance with the rate of speed of the motor, and means responsive to the motor speed for varying the deceleration and/or acceleration component of the developed motor torque in accordance with the rate of deceleration and/or acceleration of the motor whereby the delivered motor torque will remain substantially constant throughout the desired range of motor speed.

6. In a system of motor control for maintaining the torque delivered by a motor to a load to which it is connected substantially constant throughout a desired range of motor speed, means responsive to the motor speed for varying the friction component of the developed motor torque in accordance with the rate of speed of the motor, and means responsive to the motor speed for varying the component of the developed motor torque required for changing the speed of the motor in accordance with the rate of acceleration and/or deceleration of the motor whereby the delivered motor torque will remain substantially constant throughout the desired range of motor speed.

7. In a motor control system, regulator means responsive to the armature current of the motor for maintaining the developed torque of the motor substantially constant for a given motor speed, a transformer, means for continuously energizing the primary winding of said transformer with a direct-current potential proportional to the speed of the motor, means responsive to

the motor speed for varying the friction component of the developed motor torque in accordance with the rate of speed of the motor, and means responsive to the motor speed for varying the component of the developed motor torque required for changing the speed of the motor in accordance with the rate of acceleration and/or deceleration of the motor whereby the delivered motor torque will remain substantially constant throughout the desired range of motor speed.

the potential induced in the secondary winding of said transformer for causing said regulator to vary the developed motor torque in accordance with the rate of variation of the motor speed, and means responsive to the potential applied to the primary winding of said transformer for causing said regulator means to vary the developed motor torque in accordance with the rate of speed of the motor.

8. In a motor control system, regulator means responsive to the armature current of the motor for maintaining the developed torque of the motor substantially constant for any constant motor speed, a generator having a constant excitation and driven at a speed proportional to the speed of the motor, a transformer having its primary winding connected to be energized by said generator, means responsive to the potential induced in the secondary winding of said transformer for causing said regulator means to vary the developed motor torque in accordance with the rate of variation of the motor speed, and means responsive to the generator potential for causing said regulator means to vary the developed motor torque in accordance with the rate of speed of the motor.

9. In a motor control system for a strip rolling mill, a reducing roll stand comprising reducing rolls operative to subject a strip of material to tension as it is fed to the rolls, a driving motor for the reducing rolls, regulator means responsive to the armature current of the motor for controlling the excitation of the motor, means responsive to acceleration and deceleration of the motor for varying the energizing effect per unit of the motor armature current upon said regulator means, and means responsive to the speed of the motor for varying the energization of said regulator means, whereby the tension applied to the strip by the motor is maintained substantially constant throughout a desired range of motor speed.

10. In a motor control system for a tandem strip rolling mill, a drive motor for the first roll stand and a drive motor for each of the succeeding roll stands, means for simultaneously varying the speeds of said motors by armature voltage control, and control means for each of said succeeding roll stand motors, comprising, regulator means responsive to the motor armature current for controlling the excitation of the motor, means responsive to acceleration and deceleration of the motor for varying the energizing effect per unit of the motor armature current upon said regulator means, and means responsive to the speed of the motor for varying the energization of the regulator means, whereby the tension applied to the strip by each of said succeeding motors is maintained substantially constant throughout a desired range of motor speed.

11. In a control system for a plurality of drive motors each of which drives one of a plurality of work devices which simultaneously act upon a strip of material as each succeeding work device subjects the strip of material to tension as it is drawn into the work device, means for simultaneously varying the speeds of the motors by armature voltage control, and control means for each succeeding motor, comprising, regulator means responsive to the motor armature current for controlling the excitation of the motor, means responsive to acceleration and deceleration of the motor for varying the energizing effect per unit of armature current upon said regulator means, and means responsive to the speed of

the motor for varying the energization of the regulator means, whereby the tension applied to the length of material by each of the succeeding drive motors is maintained substantially constant throughout a desired range of motor speed.

12. In a control system for the drive motor of a strip rolling mill, regulator means responsive to the armature current and controlling the excitation of the motor for maintaining the developed torque of the motor substantially constant for a given motor speed, a transformer, means for continuously energizing the primary winding of said transformer with a direct-current potential proportional to the speed of the motor, means responsive to the potential induced in the secondary winding of said transformer due to changes in the energization of the primary winding for causing said regulator to vary the developed motor torque in accordance with the rate of variation of the motor speed comprising a rheostat connected to vary the effect per unit of armature current on said regulator means, electromagnetic means energized by the secondary of said transformer for varying the rheostat setting in accordance with the change in the motor speed, and means responsive to the potential applied to the primary winding of said transformer for causing said regulator means to vary the developed motor torque in accordance with the rate of speed of the motor.

13. In a system of control for a motor driving a work device which operates to tension a length of material as it is fed to the work device, regulator means responsive to the armature current of the motor for maintaining the developed torque of the motor substantially constant for a given motor speed, a transformer, means responsive to the motor speed for continuously energizing the primary winding of said transformer with a direct current potential proportional to the rate of feed of the material to the work device, means responsive to the potential induced in the secondary winding of said transformer for causing said regulator to vary the developed motor torque in accordance with the rate of variation of the rate of feed of the material to the work device, and means responsive to the potential applied to the primary winding of said transformer for causing said regulator means to vary the developed motor torque in accordance with the rate of feed of the material to the work device.

14. In a system of control for a motor driving a work device which operates to tension a length of material as it is fed to the work device, regulator means responsive to the armature current of the motor for maintaining the developed torque of the motor substantially constant for any constant motor speed, a generator having a substantially constant excitation, means driving the generator at a speed proportional to the rate of feed of the length of material to the work device, a transformer having its primary winding connected to be energized by said generator, means responsive to the potential induced in the secondary winding of said transformer for causing said regulator means to vary the developed motor torque in accordance with the rate of variation of the rate of feed of the material to the work device, and means responsive to the generator potential for causing said regulator means to vary the developed motor torque in accordance with the rate of feed of the length of material.

15. In a system of control for a motor driv-

ing a work device which operates to tension a length of material as it is fed to the work device, regulator means responsive to the armature current of the motor for maintaining the developed torque of the motor substantially constant for any constant motor speed, a transformer, means for continuously energizing the primary winding of said transformer with a direct current potential proportional to the rate of feed of the length of material to the work device, means responsive to the potential induced in the secondary winding of said transformer due to changes in the energization of the primary winding for causing said regulator to vary the developed motor torque in accordance with the 15

rate of variation of the rate of feed of the length of material comprising a variable resistor connected to vary the effect per unit of armature current on said regulator means, and electromagnetic means energized by the secondary of said transformer for varying the setting of said variable resistor in accordance with the change of the rate of feed of the length of material, and means responsive to the potential applied to the primary winding of said transformer for causing said regulator means to vary the developed motor torque in accordance with the rate of feed of the length of material to the work device.

WILLARD G. COOK.
